UNITED STATES PATENT OFFICE

FRANK A. FAHRENWALD, OF CHICAGO, ILLINOIS

HEAT RESISTING DAMPER ASSEMBLY

Application filed March 23, 1929. Serial No. 349,334.

This invention relates to improvements in a damper assembly and particularly to a damper assembly that is highly resistant to heat and is adapted to slide easily and substantially seal the flue passage when in closed position.

In the ordinary form of damper plates, especially where the damper is utilized in a flue carrying gases of high temperature, the guiding connections must be sufficiently loose to allow for expansion and contraction of the plate to avoid binding and compression strains. It is therefore difficult because of the loose connections to obtain a tight seal when the damper is in closed position. It has further been found that one piece plates used as dampers are impracticable since they are prone to excessive warping or cracking due to uneven temperature conditions encountered.

It is therefore the purpose of this invention to provide in a damper assembly a construction which permits free movement of the damper at all times and allows a substantially tight seal when the damper is in the closed position.

It is further a purpose of my invention to obtain other advantages together with a construction of damper which is not susceptible to warping or cracking by the utilization of a damper composed of a plurality of separate plates constructed according to the improvements shown in my prior Patent 1,629,689, issued May 24, 1927, and further designed so as to be particularly adaptable to the present improvements.

It is a particular feature of my invention that the damper assembly is so arranged that the damper will slide in inclined direction thereby allowing the gravitational force, due to the weight of the damper, to so act as to cause its underside to seal against the guiding connections.

A further feature of my invention resides in a construction in which the outside edges

of the damper assembly have been sufficiently widened so as to lie above the plane of the remainder of the damper construction whereby a continuous sealing edge is formed which is pressed into engagement with the guiding surfaces due to the weight of the damper.

For a further and fuller understanding of the particular objects and advantages of my invention reference may be made to the detail description in connection with the attached drawing which illustrates a preferred embodiment in which—

Figure 1 is a cross sectional elevation of a flue with the damper assembly in closed position.

Figure 2 is a vertical sectional elevation on line 2—2 of Figure 1, and

Figure 3 is a detail plan view of the damper assembly.

The construction of the damper assembly itself is quite similar to that described in my Patent No. 1,629,689, thus, I show in Figure 3 a bottom plate 1, a plurality of intermediate plates 2 and a top plate 3. The bottom plate 1 is widened at its bottom edge by a raised portion 4 on both sides for a purpose later to be described. The upper edge of the lower plate 1 is provided with spaced projections 5 which overlap the marginal edge of the next adjacent intermediate plate 2. The intermediate plate 2 is provided at its lower edge with similar downwardly extending projections 6 which extend between the projections 5. The remaining connections between the plates are made in a similar manner by upwardly extending projections 5 and downwardly extending projections 6. The projections are adapted to be arranged on the same side of the damper assembly, preferably on the cooler side, since the excessive heat of the other side may tend to burn off projections. The projections 5 and 6 cooperate to prevent warping longitudinally of the plates due to unequal temperature conditions. The side edges of the plates are pref-

erably formed with T-shaped heads 7, as will be seen from Figure 2, which slide in the marginal assembling sides 8 and 9. The members 8 and 9 are preferably channel sections having longitudinal T-shaped slots. The members 8 and 9 are closed at their lower ends, as indicated at 10, to provide a seat for the lower plate 1 and have stop pins 11 at their upper ends preventing upward movement of the upper plate 3, however, a small clearance is allowed to permit expansion.

The upper plate 3 is designed with a widened upper edge 12 corresponding to the lower edge 4 of the lower plate 1. The outer lateral surfaces of the widened edges 4 and 12 and the channel members 8 and 9 form continuous rims on both surfaces of the damper assembly that lie in planes outwardly spaced from the plane of the surface of the damper plates and the locking projections. The upper edge 12 is further provided with an eye 13 for attachment to a suitable connection 14 adapted to be connected to an operating cable 15, as will be seen in Figure 1.

Figure 1 illustrates the preferred arrangement of my damper assembly in connection with a flue. I show at 16 any ordinary type of melting furnace or other form of heater from which the waste gases flow. From the furnace 16 extends the horizontal flue 17 to the uptake 18. The walls of the flues are suitably formed of fire brick 19 and a heat resisting liner 20. As shown in my embodiment, the flue is of rectangular cross-section and has side walls 21-22 and upper and lower walls 23-24, however, a similar construction could be adapted to a circular flue by building a suitable rectangular shaped opening within the flue. I mount in the side walls 21-22 inclined channel members 25-26 which receive the side channels 8 and 9 of the damper assembly. In the bottom wall 24 of the flue a transverse channel member 27 is provided to receive the widened edge 4 on the lower damper plate. The damper assembly slides between spaced guide plates 28-29 mounted in an opening through the upper wall 23. The operating cable 15 is suitably guided by pulleys 30 and 31. The channels 25-26 and 27 and the guides 28-29 may, if so desired, be made up as an integral frame set into the walls of the flue. The guide frame is adapted to loosely receive the damper assembly so that it will be free to slide without binding strains due to unequal expansion.

Since the damper assembly is held in an inclined plane, it is apparent that its lower surface only will be in direct contact with the supporting and guiding frame and the weight of the damper assembly will assist in forcing its raised continuous rim into sealing engagement with the guiding frame. Furthermore, the weight of the damper as-

sembly positively urges it to slide to a closed position.

It will, therefore, be apparent that the damper assembly forms a substantially gas-tight seal when in closed position. It is, of course, to be understood that the damper herein shown is not adapted to be used in installations where there is a high pressure of gas, but it is principally adapted to be used in flues for gas of high temperature and gas which may carry dust rendering it impossible to use precision valves. It will be noted that expansion is allowed in upward direction of the damper plates and besides expansion is allowed by the loose connection between the U-shaped heads 7 and the slots within the marginal side members 8 and 9. The T-shaped head further makes it necessary for the gas to take a tortuous path around the sealing edges therefore eliminating the tendency to leakage.

I claim:

1. In combination, a high temperature rectangular gas flue having an inclined damper receiving opening extending across the top wall, inclined damper receiving grooves in its side walls and a damper sealing groove in its bottom wall between the lower ends of said inclined grooves, a damper assembly slidably associated with said opening and grooves of said flue, said damper assembly comprising a pair of damper frame guide bars fitting in and conforming in shape to said inclined grooves and adapted to gravitally seat in sealing engagement with the lower side walls of said inclined grooves, a plurality of sectional damper plates slidably supported by said guide bars and adapted to gravitally seat in sealing engagement with each other and with the guide bars, the bottom damper plate having the bottom edge adapted to fit in and conforming in shape to the groove in the bottom wall of said flue, the upper damper plate having a top edge fitting in and adapted to seat against the lower side wall of the opening in the top wall of said flue and means connected to said top damper plate for moving the damper assembly.

2. In combination, a high temperature rectangular gas flue, a rectangular damper guide frame fixed with respect to said gas flue in inclined position, said guide frame including an opening for the admission of a damper assembly through the top wall of said flue, damper guiding grooves and a damper seating groove in the bottom wall, a damper assembly slidably associated with said damper guide frame, said damper assembly comprising a pair of guide bars slidably fitting in the side grooves of said damper guide frame and adapted to gravitally seat against one edge of said guide grooves, a plurality of damper plates slidably associated with said guide bars adapted to gravi-

tally seat in bearing engagement with each other and with an edge of each of said guide bars, the bottom damper plate having its bottom edge formed to fit in and gravitally seat against an edge of the bottom groove of said damper guide frame, the top damper plate having its upper edge formed to closely fit the top opening in said damper guide frame and adapted to gravitally seat against the side wall of said opening and means connected to said top plate for moving said damper assembly.

Signed at Chicago, Illinois, this 12th day of March, 1929.

FRANK A. FAHRENWALD.
